RACK FOR DRILL BITS, TAPS AND THE LIKE

Olie A. Nannfeldt, Pokagon Township, Cass County,
Mich. (3102 M-40 North, Niles, Mich.)

Filed July 15, 1965, Ser. No. 86,168

Term of patent 7 years

(Cl. D80—9)

FIGURE 1 is a perspective view of a rack for drill bits, taps and the like embodying my new design;

FIGURE 2 is a front elevational view thereof;

FIGURE 3 is a rear elevational view thereof;

FIGURE 4 is a side elevational view thereof;

FIGURE 5 is a top plan view thereof; and

FIGURE 6 is a bottom view thereof.

The broken line representation of an oil can, drills and taps in FIGURE 1 is for the purposes of illustration, only. The essential features of my design reside in the recess for an oil can in combination with the tapered, bevelled side edges and bevelled front edges in association with the rack as shown.

I claim:

The ornamental design for a rack for drill bits, taps and the like, as shown and described.
